UNITED STATES PATENT OFFICE

CHARLES M. HORTON, OF ELIZABETH, NEW JERSEY, ASSIGNOR TO THE SINGER MANUFACTURING COMPANY, A CORPORATION OF NEW JERSEY.

SEWING-MACHINE.

932,391.

Specification of Letters Patent. Patented Aug. 24, 1909.

Application filed June 13, 1908. Serial No. 438,275.

To all whom it may concern:

Be it known that I, CHARLES M. HORTON, a citizen of the United States, residing at Elizabeth, in the county of Union and State 5 of New Jersey, have invented certain new and useful Improvements in Sewing-Machines, of which the following is a specification, reference being had therein to the accompanying drawings.

This invention relates to an improvement in sewing machines for producing groups of stitches in sewing on buttons, binding the edges of buttonholes and other operations involving the application of groups of 15 stitches to the work.

The invention has for its primary object the provision of a work-holder in which the work will be invariably clamped before the beginning of a stitching operation and maintained firmly clamped throughout such stitching operation and released only at the completion of the cycle of operation of the machine.

It has for its further object means of control of the stop-motion device utilized in opening the work-holder whereby the arrest of the machine is insured at the completion of each cycle of operation, the actuation of the stop-motion device to effect the continued 30 operation of the machine from one stitching period to another being prevented by means beyond the control of the operator or attendant.

The invention consists in the construction 35 and arrangement of mechanism herein shown and described and set forth in the appended claims.

In the accompanying drawings, Figure 1 is a rear side elevation of a flat button sewing machine of the well-known Singer type 40 embodying the present invention. Fig. 2 is a similar side elevation of the work-clamp with its operating means, with the exception of the cam-wheel which is omitted to expose 45 the parts behind the same; and Fig. 3 a plan view of such parts with the bracket-arm of the machine in section. Fig. 4 is a perspective view of the stop-motion device and the clamp operating means. Fig. 5 is a detail 50 plan view of the interengaging members of the stop-motion device and the clamp controlling mechanism. Fig. 6 is a detail view 55 of the thread pulling device.

As shown in my prior United States patent of December 19, 1905, No. 807,676, rep-

resenting the machine in which the present improvement is embodied, the machine is provided with a hollow bed 1 affording a support for the bed-plate 2 of the machine frame, upon which is mounted the usual 60 bracket-arm 3. The main-shaft 4 is journaled in the bracket-arm and provided at its forward end with a take-up cam-cylinder 5 having the usual crank-pin connected by means of the pitman 6 with a lateral stud 65 upon the needle-bar 7 which is provided with an eye-pointed needle 8 co-operating with a shuttle mounted in the shuttle-race 9 in a manner well-known. The main-shaft 4 carries at its rearward end the usual fast and loose pulleys 10 and 11, the former being provided with the stopping cam 12 with substantially snail-shaped periphery formed with the notch or recess 13 entered by the reduced upper end 14 of the spring-pressed 70 stop-bolt 15 slidingly mounted in the vibrating stop-lever 16 which is fulcrumed in a manner well-known in the forked swivel-block 17 fitted to the bearing 18 extended 75 from the back of the bracket-arm.

The lever 16 carries the belt-shifting arm 19 embracing the power transmitting belt. The lever 16 is thrown forwardly against the stress of its spring 16 to disengage the stop-rod 15 from the stopping cam 12, by engagement therewith of the depending arm 20 of an angular lever having a lateral arm 21 connected with the usual treadle device by means to be hereinafter described; being maintained in retracted position by means 80 of a latch-lever 22 having a rearwardly extending arm provided with a hook 23 adapted to engage a correspondingly shaped tooth 24 formed in the rearward side of the lever 16, being held normally in contact with the side 85 face of the latter by means of a spring 25. The forwardly projecting arm of the latch-lever is provided with a lateral wedge-shaped projection 26 normally lying in the path of the tripping points 27 carried by the cam-wheel 28 fixed upon the shaft 29 which is mounted in a bearing boss 30 extending laterally from the upright portion of the bracket-arm 3, the shaft 29 being provided at its opposite end, within the bracket-arm, with the worm-wheel 31 meshing with a worm 32 upon the main-shaft 4. The tripping of the latch-lever 22 serves to release the stop-lever 100 105 110 115 120 125 130 135 140 145 150 155 160 165 170 175 180 185 190 195 198 200 205 210 215 220 225 230 235 240 245 250 255 9999

end 14 of the bolt 15 into operative engagement with the periphery of the stopping cam 12, whose rotation is retarded thereby and finally arrested by entrance of the bolt head 5 14 into the cam-notch 13, but not until the momentum of the connected parts has caused the cam to throw the lever 16 laterally upon its swivel-block 17 in opposition to a buffer-spring 33 acting upon a plunger-rod 34 10 housed within a cylindrical casing 35 carried by the machine frame, the inner end of the plunger-rod 34 being adapted to engage the side face of the stop-lever 16. The lower end of the stop-lever 16 is provided with an 15 aperture 16^x entered by the extremity of an arm 35^x of a cutter-actuating rock-lever, whereby the over-throw of the machine serves to actuate suitable cutting knives to sever the upper and lower threads of the 20 stitching mechanism, as described in my former United States Patent No. 807,676.

The traveling work-holder of the present machine is composed of a lower jaw afforded by a flat plate 36 and a relatively 25 movable upper jaw 37, shown in the drawings as one of the members of a button-clamp. The lower jaw or work-supporting plate 36 is secured by means of a screw 38 to the forward end of a slide-bar 39 upon 30 the rearward end of which is mounted a block 40 recessed to receive the downturned rearward end 41 of the supporting arm 42 pivotally mounted therein and carrying at its forward end the upper clamping jaw 37. The 35 top of the block 40 is channeled to receive the rearward end of a plate 43 clamped thereon by means of the screw-bolt 44 and having adjacent the same a stop-screw 45 adapted to engage the top of the arm 42 40 to limit its upward movement when the work-clamp is opened for the introduction or release of the work. The clamp-arm 42 is provided near its forward end with an upwardly projecting stud 46 provided with 45 a socket 47 having a hemispherical cavity with screw-threaded sides entered by a similarly threaded bushing 48 with a hemispherical lower end and a central aperture to receive the shank of the rod 49 having at its 50 lower end the ball 50 seated in the spherical cavity of the socket 47 and having its upper threaded end introduced in a similarly threaded socket of the thrust-rod 51 provided with a spherical head 52.

55 Upon the upright portion of the bracket-arm is fulcrumed by means of the screw-stud 53 a rock-lever having a forwardly extending arm 54 provided in its free end with an aperture flared at the top to form a hemispherical socket 55 and with a rearwardly extending arm 56. The rod 51 extends upwardly through the aperture in the arm 54 of the rock-lever and its spherical head 52 is seated in the socket 55 therein, being yieldingly maintained in position by means of a

flat spring 57 whose outer end is formed with a slight cavity fitted to the top of the ball 50 and whose rearward end is secured by means of fastening screws 58 upon a projecting seat on the upper edge of the arm 54. 70 The rock-lever is normally maintained with its arm 54 elevated to open the work-holder by means of a spring 59 interposed between a lateral pin 60 upon the rearward arm 56 and a stud 61 upon a bracket 62 secured by 75 means of screws 63 upon the bed-plate.

The rearward end of the lever-arm 56 is forked at 56^x to embrace the upper end of a link-member 64 connected therewith by means of a pivotal screw 65 and having its 80 lower end interposed between and connected by means of a screw-pin 66 with the upper ends of two parallel links 67 and 68 which are in turn embraced between and pivotally connected by means of the screw-pin 69 85 with the spaced ears 62^x of the bracket 62. The link 64 forms, with the links 67 and 68, a toggle connection between the rearward end of the lever-arm 56 and the fixed bracket 62, the straightened position of the toggle 90 being determined by engagement with the forward edge of the link 64 of the adjustable stop-screw 70 carried by the upwardly projecting and offset finger 67^x of the link 67 and provided with a lock-nut 71 for securing 95 the same in position. As will be observed by reference to the drawings, the link 68 is extended to form a downwardly projecting arm 68^x which is formed with a perforation adapted to receive the eyed end of a forwardly extending shift-rod 72 having a handle 73 at its forward end by means of which the toggle may be bent and straightened to rock the lever 54 56 in opening and closing the work-clamp.

105 Mounted upon the pivotal screw-pin 69 intermediate the link members 67 and 68 is an angular lever having an upwardly extending short arm 74 carrying a lateral pin 75 adapted to engage the forward edge of 110 the link member 67, and having a rearwardly extending arm 76 connected at its extremity by means of the screw-pin 77 with the eyed lower end of a rod 78 having a screw-threaded upper end passed through 115 the apertured rearward end of the arm 21 of the clutch-shifting lever and provided above the same with the thrust-nut 79 and jam-nut 80. The shoulder upon the rod 78 afforded by the nut 79 is so adjusted that 120 when the rod 78 is drawn downwardly for shifting the stop-lever 16 to start the machine, the nut 79 is disposed slightly above the lever-arm 21 to provide a certain amount of lost-motion, whereby the initial movement of the rod 78 is to depress the lever-arm 76 so as to practically straighten the toggle 64, 67, 68, before the stop-bolt 15 is 125 wholly disengaged from the stopping cam 12, thus insuring the closing of the clamp 130

upon the work before the final release of the stopping cam fixed upon the main-shaft to permit the starting of the stitching mechanism.

The link-member 64 of the toggle is provided with an upwardly extending finger 81 having its forward edge beveled at 82 to form a cam portion adapted to be engaged by the extremity of a tripping finger 83 having a foot-piece 84^a secured by means of screws 85^a to the rearward face of the stop-lever 16 in such position that the point or operative extremity of the finger 83 is in operative relation with the cam portion of the finger 81 when the toggle is straightened and the stop-lever 16 has been thrown into operative relation with the stopping cam 12 just prior to the stoppage of the machine. The lateral movement of the stop-lever 16 due to the over-throw of the machine caused by the engagement of the stop-bolt 15 with the notch 13 of the stopping cam 12 causes the advance of the finger 83 outward and the engagement of its operative extremity with the cam portion of the finger 81, by means of which the latter is thrown backwardly and the link is shifted forwardly a sufficient distance to bring the pivotal pin 66 of the toggle device forward of the neutral position of the toggle, whereby the resistance to the action of the spring 59 upon the rock-lever 54 56 is removed and the latter is permitted to tilt upon its fulcrum 53 to open the work-holder.

The common connection between the stop-motion and clamp-operating devices and the treadle or other operating means beneath the machine support comprises a block 84 secured to the upper portion of the rod 78 and formed with lateral spaced lugs 84^a embracing the adjacent ends of a pair of spaced links 85 and 86 pivotally attached thereto by means of screw-pins 87. Intermediate the opposite ends of such links is pivotally connected by means of the screw 88 the reduced upper end of a rod 89 having an apertured lower end entered by the hooked upper end of a pull-rod 90 extended downwardly beneath the machine support for connection with a suitable treadle device and surrounded by a spring 91 interposed between a fixed thrust collar 92 upon said rod and a washer 93 seated upon the supporting table 94, which is provided with a slot 95 through which the rod 90 passes.

The double link-member 85 86 is normally maintained in upright and substantially parallel relation with the rod 78 by means of a spring 96 having one end secured to a bent pin 97 upon the block 84 and the other end attached to a lateral pin 98 upon the link 85. The clutch operating parts are therefore normally maintained in such relation that the maintenance of the rod 90 in lowered or operative position will

act through the double link-member 85 86 and connecting rod 89 to confine the lever-arms 21 and 76 in depressed or operative position, wherein the stop-lever 16 is in its forward or inoperative position and the clamp controlling toggle 64, 67 68 is in straightened or operative position. As the arms 21 and 76 are not positively connected with the parts which they operate, repeated accidental actuations of the treadle-rod 90 during the cycle of operation of the machine would obviously have no effect upon the operative parts until the tripping of the stop-motion by engagement of the tripping points 27 of the cam-wheel 28 with the latch-lever 22; but without some special provision against such contingency, the drawing down of the rod 78 or maintenance of the same in lowered position at about the time the stop-motion device is tripped would restore the stop-lever 16 to inoperative position or prevent its backward movement under the action of its spring, whereby the machine would be caused to perform a succeeding cycle of operation after an initial stitching operation, which would evidently injure the work. To avoid this contingency, the link-member 86 is provided with an upward extension having a forwardly projecting laterally offset finger 86^a which lies, when the rod 78 is depressed, normally in the path of movement of the rearwardly extending arm 99 of a lever pivotally mounted upon the machine frame at 100 and provided with a forwardly projecting arm 101 whose operative edge lies normally directly beneath the tooth or projection 26 of the latch-lever 22, where it is maintained by means of a spring 102 interposed between the same and a screw-stud 103 upon the socket 35.

As the tripping point 27 of the cam-wheel 28 approaches the tooth 26 of the lever 22 from below, it engages and shifts the lever 99 101 upon its fulcrum 100 so as to displace the double link-member 85 86 laterally to shift the pivotal pin 88 out of alignment with the rod 90 and pivotal pin 87, so as to bend the toggle composed of the double link-member 85 86 and the connecting rod 89, whereby the succeeding tripping of the stop-motion to release the stop-lever 16 permits the latter to assume its operative relation with the stopping cam 12, and rock the angular lever 20 21 which raises the rod 78 and rocks the angular lever 74 76 to release the clamp closing toggle, the parts above mentioned being thus brought into the position represented in Fig. 4, in which the stop-lever 16 is about to be shifted laterally under the momentum of the moving parts of the machine to cause the cutting of the threads and engagement of the actuating finger 83 with the finger 81 to bend the work-clamp closing toggle in finally opening the work-clamp. As soon as the treadle-rod

90 is released, the spring 91 serves to restore it to raised inoperative position, which enables the spring 96 to return the double link-member 85 86 to initial vertical position in 5 readiness for a succeeding actuation of the stop-motion device to produce a further stitching operation.

The variable closing of the clamp of the present improvement upon materials of different thickness would cause a variation in the initial retracted position of the thread-pulling finger, were the latter operatively connected with the upper jay of the work-clamp, and the present invention is designed 10 to insure that the thread-pulling finger shall invariably be retracted sufficiently beyond the needle-path which it crosses in its operative movement to insure against interference with the needle in the stitching operation. 15 To this end, the head of the bracket-arm is provided with a depending lug 104 upon which is pivotally mounted a plural-armed lever of which the depending arm 105 carries a wire thread-engaging finger 106 with 20 laterally bent lower end normally lying at one side of the needle-path but adapted to cross the same when the needle is in raised position and of which lever a lateral arm 107 is embraced by a laterally extending hook 25 108 upon the lower end of an inclined arm 109 having its upper end or shank 110 secured for vertical adjustment by means of the set-screw 111 in a socket 112 at the forward end of the lever-arm 54. As will be 30 observed, the outer end of the lever-arm 105 is formed with a laterally forked lug 105* through which passes the wire shank of the finger 106 which is formed at its upper end with the loop 106* adjustably secured upon the 35 arm 105 by means of the fastening screw 113.

While the rise of the rock-lever arm 54 under the action of the lifting spring is determined by the stop-screw 45 limiting the rise of the clamp-arm 42, it will be observed 45 that the downward movement of the arm 54 is positively determined by the straightening of the toggle 64 67 68, whereby the downward movement of the hook 108 serves to invariably retract the thread-pulling 50 finger 106 to initial position at the side of the needle-path where it is maintained while the clamp remains closed during each stitching operation; any difference in thickness of the work serving to vary the spacing of the 55 clamp-jaws 36 and 37 when closed being accommodated by the yielding of the connecting link or thrust-rod 51 in opposition to the spring 57 carried by the rock-lever arm 54.

As described in my Patent No. 807,676, before mentioned, the work-clamp of the present machine has imparted to it a transverse reciprocating motion by means of the cam-track 114 in the rear face of the cam, which is entered by a roller-stud upon the rock-lever 115 fulcrumed at 116 upon a fixed

bracket 117 secured to the bed-plate and having operative connections beneath the bed-plate including a link 118 and a bell-crank member 119 with a laterally sliding block 120 connected to the clamp-plate 39. 70 The clamp-plate 39 is further provided with means (not fully shown) including a cam-track upon the opposite face of the cam-wheel 28, whereby it receives longitudinal reciprocating movements. As the specific 75 means for producing the travel of the work-clamp in relation to the stitch-forming mechanism forms no part of the present invention, further reference thereto is deemed unnecessary in the present application. 80

From the foregoing description it will be observed that in the initial positions of the various parts of the machine represented in Fig. 1, the work to be stitched is introduced between the clamp-jaws 36 and 37 and the 85 jointed treadle-rod 89 90 drawn downwardly in opposition to its spring 91, the lost-motion between the top of the lever-arm 21 and the thrust-nut 79 permitting the initial movement of the depending rod 78 90 to depress the lever-arm 76 and practically straighten the clamp-closing toggle preparatory to the rocking of the angle-lever 20 21 to extreme position for disengagement of the stop-bolt 15 from the engaging shoulder 95 of the stopping cam 12, the belt-shifting arm 19 being simultaneously moved to throw the power belt upon the fast pulley 10; whereby the clamp is first closed and the stitch-forming and feeding mechanisms are then set in 100 operation. Although the treadle-rod is ordinarily released immediately after the tripping of the stop-motion device to start the machine, the maintenance of the treadle depressed during the operation of the machine 105 is provided for in the present improvement as already described. In its lowered position, the treadle rod maintains the tripping finger 86* in the path of movement of the lever 99 101, as represented in Fig. 2, the 110 lever-arms 21 and 76 remaining also in their lowered positions. As one of the tripping points 27 of the cam-wheel 26 approaches active position, it first engages the arm 101 of the release lever whose other arm 99 engages and thrusts aside the projecting finger 86* of the link member 85 86 which shifts such link-member out of normal substantially parallel relation with the rod 78, and bends the toggle afforded by such link-member in conjunction with the treadle-rod section 89; and the succeeding tripping of the latch-lever 22 by the tripping point 27 disengages such latch-lever 115 from the stop-lever 16 and causes the latter to move backwardly under the action of its spring into operative relation with the stopping cam 12, the angle-lever 20 21 being thereby rocked to lift the rod 78 and remove the confining pin 75 from engagement with 120 125 130

the link-member 67 of the clamp-closing toggle device, which position of the parts is represented in Fig. 4 just prior to the opening of the clamp. The momentum of the rotating parts operates at this point by the engagement of the opposed shoulder of the notch 13 of the stopping cam 12 with the head 14 of the stop-bolt 15 to throw the stop-lever 16 laterally in opposition to the spring 33, which first causes the severing of the threads under the action of the bell-crank lever 35* and finally causes the bending of the clamp-closing toggle to permit the clamp to open under the action of the spring 59 by the engagement of the cam-finger 85 upon the stop-lever 16 with the extension finger 81 of the link-member 64.

Having thus set forth the nature of the invention, what I claim herein is:—

1. In a sewing machine, the combination with stitch-forming mechanism, of a traveling work-holder having work-clamping jaws one of which is movable toward and from the other, a rock-lever mounted upon a fixed fulcrum and having a universal connection with the movable jaw of said work-holder, means including a toggle device connected with said rock-lever for controlling the position of the same, and means for straightening and bending said toggle to close and open the work-holder.

2. In a sewing machine, the combination with stitch-forming mechanism, of a traveling work-holder having work clamping jaws one of which is fixed upon a supporting arm and movable toward and from the other, a rock-lever mounted upon a fixed fulcrum, a link intermediate an arm of said rock-lever and the clamp-jaw supporting arm and having universal-joint connections with each, means including a toggle device connected with said rock-lever for controlling the position of the same, and means for straightening and bending said toggle to close and open the work-holder.

3. In a sewing machine, the combination with stitch-forming mechanism, of a traveling work-holder having work clamping jaws one of which is fixed upon a supporting arm and movable toward and from the other, a rock-lever mounted upon a fixed fulcrum, a link of adjustable length intermediate an arm of said rock-lever and the clamp-jaw supporting arm and having universal joint connections with each, means including a toggle device connected with said rock-lever for controlling the position of the same, and means for straightening and bending said toggle to close and open the work-holder.

4. In a sewing machine, the combination with stitch-forming mechanism, of a traveling work-holder having work-clamping jaws one of which is movable toward and from the other and a supporting arm carrying said movable jaw, a rock-lever mounted

upon a fixed fulcrum, a link intermediate an arm of said rock-lever and the clamp-jaw supporting arm with which the same is connected by means of ball-and-socket joints, means including a toggle device connected with said rock-lever for controlling the position of the same, and means for straightening and bending said toggle to respectively close and open the work-holder.

5. In a sewing machine, the combination with stitch-forming mechanism, of a traveling work-holder having work-clamping jaws one of which is movable toward and from the other and a supporting arm carrying said movable jaw, a rock-lever mounted upon a fixed fulcrum, and provided with an arm extending above the clamp-jaw supporting arm and having an aperture with a socket in the upper side, a link passing through the aperture in said rock-lever arm and having a spherical head seated in the socket thereof with its opposite end connected by a universal joint with the clamp-arm, a spring secured to said rock-lever arm and bearing upon the head of said link, means including a toggle device connected with said rock-lever for controlling the position of the same, and means for straightening and bending said toggle to respectively close and open the work-holder.

6. In a sewing machine, the combination with stitch-forming mechanism, of a traveling work-holder having work-clamping jaws one of which is movable toward and from the other and a supporting arm carrying said movable jaw, a rock-lever, a link intermediate an arm of said rock-lever and the clamp-jaw supporting arm and having universal-joint connections with each, a spring connected with said rock-lever for tilting the same to raise the movable clamp-jaw, a stop-arm overlying the clamp-jaw supporting arm and adapted to limit the rising movement of the movable clamp-member, means including a toggle device connected with said rock-lever for controlling the position of the same, and means for straightening and bending said toggle to respectively close and open the work-holder.

7. In a sewing machine, the combination with stitch-forming mechanism, of a traveling work-holder having work-clamping jaws one of which is movable toward and from the other and a supporting arm carrying said movable jaw, a rock-lever, a link intermediate an arm of said rock-lever and the clamp-jaw supporting arm and having universal-joint connections with each, a spring connected with said rock-lever for tilting the same to raise the movable clamp-jaw, a stop-arm overlying the clamp-jaw supporting arm, and an adjustable contact screw carried by the same and adapted to engage the clamp-arm, means including a toggle device connected with said rock-lever for con-

- trolling the position of the same, and means for straightening and bending said toggle to respectively close and open the work-holder.
5. In a sewing machine, the combination with stitch-forming mechanism, of a traveling work-holder having work-clamping jaws one of which is movable toward and from the other, a rock-lever operatively connected 70 with the movable jaw of said work-holder, means including a toggle device connected with said rock-lever for controlling the position of the same, and means acting independently upon different members of said 75 toggle device for respectively straightening and bending the same to close and open the work-holder.
10. In a sewing machine, the combination with stitch-forming mechanism, of a traveling work-holder having work-clamping jaws one of which is movable toward and from the other, a rock-lever operatively connected 80 with the movable jaw of said work-holder, means including a toggle device connected with said rock-lever for controlling the position of the same, means controlled by the starting and stopping of the machine for 85 straightening and bending the toggle device to respectively close and open the work-holder, and means connected with the toggle device and independent of the first-named controlling means and accessible adjacent the 90 work-clamping jaws whereby the toggle device may be operated while the machine is at rest.
9. In a sewing machine, the combination with the frame comprising a bed-plate and an 95 overhanging bracket-arm, and stitch-forming mechanism mounted therein, of a traveling work-holder having work-clamping jaws one of which is movable toward and from the other, a rock-lever operatively connected 100 with the movable jaw of said work-holder, means including a toggle device connected with said rock-lever for controlling the position of the same, means controlled by the starting and stopping of the machine for 105 straightening and bending the toggle device to respectively close and open the work-holder, and means connected with the toggle device and independent of the first-named controlling means and extended beneath the 110 bed-plate to a position adjacent the work-clamping jaws whereby the toggle device may be operated while the machine is at rest.
10. In a sewing machine, the combination 115 with the frame comprising a bed-plate and overhanging bracket-arm, and stitch-forming mechanism mounted therein, of a traveling work-holder having work-clamping jaws one of which is movable toward and from 120 the other, a rock-lever operatively connected with the movable jaw of said work-holder, a toggle device disposed above said work-plate and having one of its members connected with said lever and another of its members 125 extended downwardly beneath the bed-plate for controlling the position of said rock-lever, means controlled by the starting and stopping of the machine for straightening and bending the toggle device to respectively close and open the work-holder, and a rod 130 connected with said extension of the toggle member and extending forwardly beneath the bed-plate adjacent the work-clamp jaws for controlling the toggle while the machine is at rest.
11. In a sewing machine, the combination with stitch-forming mechanism, of a traveling work-holder having work-clamping jaws one of which is movable toward and from the other, a rock-lever operatively connected with the movable jaw of said work-holder, means including a toggle device connected with said rock-lever for controlling the position of the same, and means acting independently upon different members of said 75 toggle device for respectively straightening and bending the same to close and open the work-holder.
12. In a sewing machine, the combination with stitch-forming mechanism, of a traveling work-holder having work-clamping jaws one of which is movable toward and from the other, a rock-lever operatively connected 85 with the movable jaw of said work-holder, means including a toggle device connected with said rock-lever for controlling the position of the same, manually controlled means acting upon one of the members of said toggle device for straightening the latter and automatically acting means engaging another member of said toggle device for bending the latter.
13. In a sewing machine, the combination with stitch-forming mechanism and a stop-motion device including a swinging stop-lever for controlling the action of said stitch-forming mechanism, of a traveling work-holder having work-clamping jaws one of which is movable toward and from the other, a rock-lever operatively connected with the 100 movable jaw of said work-holder, a toggle device connected with said rock-lever for controlling the position of the same, and having one of its members disposed within the range of movement of said stop-lever 105 whereby the toggle is adapted to be bent to permit the opening of the work-clamp, and manually controlled means acting upon another member of said toggle for straightening the latter to close the work-clamp.
14. In a sewing machine, the combination 110 with the main-shaft and stitch-forming mechanism operatively connected therewith, and a stop-motion device including a swinging stop-lever, a spring-pressed bolt and a stopping cam upon the main-shaft into and out of operative relation with which said bolt is adapted to be carried by the stop-lever, of a traveling work-holder having work-clamping jaws one of which is movable toward and from the other, a rock-lever operatively connected with the movable jaw of said work-holder, a toggle device connected with said rock-lever for controlling the position of the same, and having one of its members disposed within the range of movement of said stop-lever whereby the toggle is adapted to be bent to permit the opening of the work-holder, a lever adapted 120 to engage a member of said toggle device 125

to straighten the same in closing the clamp, and a common manual controlling device operatively connected with the stop-lever and the toggle-straightening lever whereby a single actuation serves to successively straighten the toggle to close the clamp and to shift the stop-lever to permit the rotation of the main-shaft for a stitching operation.

15. In a sewing machine, the combination with the main-shaft and stitch-forming mechanism operatively connected therewith, and a stop-motion device including a stop-lever fulcrumed to swing both longitudinally and transversely of the main-shaft and carrying a spring-pressed bolt, a stopping cam upon the main-shaft into and out of operative relation with which said bolt is adapted to be carried by the stop-lever, a spring for pressing said stop-lever longitudinally of the main-shaft with its bolt in operative engagement with the stopping cam, an automatically controlled latch for maintaining said stop-lever in retracted inoperative position, and a spring-pressed buffer for normally holding the stop-lever against transverse movement when in operative relation with the stopping cam, of a traveling work-holder having work-clamping jaws one of which is movable toward and from the other, a rock-lever operatively connected with the movable jaw of said work-holder, a toggle device connected with said rock-lever for controlling the position of the same, and having one of its members disposed within the range of transverse movement of said stop-lever whereby the toggle is adapted to be bent upon the stopping of the machine to permit the opening of the work-holder, and a manually actuated controlling device operatively connected with the stop-lever and a member of the toggle device whereby a single actuation serves to successively straighten the toggle to close the clamp and to shift the stop-lever into inoperative relation with the stopping cam to permit the rotation of the main-shaft for a stitching operation.

16. In a sewing machine, the combination with the main-shaft and stitch-forming mechanism operatively connected therewith, and a stop-motion device including a swinging stop-lever, a spring-pressed bolt carried by said stop-lever, and a stopping cam upon the main-shaft into and out of operative relation with which said bolt is adapted to be carried by the stop-lever, of a traveling work-holder, means including a reciprocating rod whereby the work-holder is closed and the stop-lever is shifted to disengage its stop-bolt from the cam, automatically acting means for returning the stop-lever to initial position in stopping the machine, means connected with the stop-motion device whereby the work-holder is opened, a treadle-rod, a normally operative connection between the

treadle-rod and said reciprocating rod, and means acting automatically upon said connection for rendering the same inoperative at the end of a cycle of operation of the machine.

70

17. In a sewing machine, the combination with the main-shaft and stitch-forming mechanism operatively connected therewith, and a stop-motion device including a swinging stop-lever, a spring-pressed bolt carried by said stop-lever, a stopping cam upon the main-shaft, a spring for shifting said stop-lever into operative position to carry the stop-bolt into operative relation with the stopping cam, and a latch-lever for maintaining said stop-lever in retracted position, of a traveling work-holder, means including a reciprocating rod whereby the work-holder is closed and the stop-lever is shifted to disengage its stop-bolt from the cam, a pattern cam provided with a tripping point acting upon said latch-lever to disengage it from the stop-lever, means connected with the stop-lever whereby the work-holder is opened, a treadle-rod, a normally operative connection between the treadle-rod and said reciprocating rod, and means controlled by the tripping point of the pattern cam for rendering said connection inoperative during the release of the stop-lever for stopping the machine.

80

18. In a sewing machine, the combination with the main-shaft and stitch-forming mechanism operatively connected therewith, and a stop-motion device including a swinging stop-lever, a spring-pressed bolt carried by said stop-lever, a stopping cam upon the main-shaft, a spring for shifting said stop-lever into operative position to carry the stop-bolt into operative relation with the stopping cam, and a latch-lever for maintaining said stop-lever in retracted position, of a traveling work-holder, means including a reciprocating rod whereby the work-holder is closed and the stop-lever is shifted to disengage its stop-bolt from the cam, a pattern-cam provided with a tripping point acting upon said latch-lever to disengage it from the stop-lever, means connected with the stop-lever whereby the work-holder is opened, a treadle-rod, a toggle connection between the treadle-rod and said reciprocating rod, and a trip-lever disposed adjacent said latch-lever and in the path of movement of said tripping point and adapted to engage a member of said toggle connection to laterally displace the same as the latch-lever is shifted to release the stop-lever in stopping the machine.

100

19. In a sewing machine, the combination with the main-shaft and stitch-forming mechanism operatively connected therewith, and a stop-motion device including a swinging stop-lever, a spring-pressed bolt carried by said stop-lever, a stopping cam upon the

110

115

120

130

main-shaft, a spring for shifting said stop-lever into operative position to carry the stop-bolt into operative relation with the stopping cam, and a latch-lever for maintaining said stop-lever in retracted position, of a traveling work-holder, means including a reciprocating rod whereby the work-holder is closed and the stop-lever is shifted to disengage its stop-bolt from the cam, a pattern-cam provided with a tripping point acting upon said latch-lever to disengage it from the stop-lever, means connected with the stop-lever whereby the work-holder is opened, a treadle-rod, a toggle connection between the treadle-rod and said reciprocating rod, a spring for yieldingly retaining the members of the toggle connection in parallel relation with said reciprocating rod, and a trip-lever disposed adjacent said latch-lever and in the path of movement of said tripping point and adapted to engage a member of said toggle connection to laterally displace the same in opposition to its retaining spring as the latch-lever is shifted to release the stop-lever in stopping the machine.

20. In a sewing machine, the combination with the main-shaft and stitch-forming mechanism operatively connected therewith, and a stop-motion device including a swinging stop-lever, a spring-pressed bolt carried by said stop-lever, a stopping cam upon the main-shaft, a spring for shifting said stop-lever into operative position to carry the stop-bolt into operative relation with the stopping cam, and a latch-lever for maintaining said stop-lever in retracted position, of a traveling work-holder having work-clamping jaws one of which is movable toward and from the other, a rock-lever operatively connected with the movable jaw of said work-holder, a toggle device connected with said rock-lever for controlling the position of the same, angle-levers independently

fulcrumed and provided with lateral arms, and angularly disposed arms adapted to engage respectively a member of said toggle-device for closing the work-holder and the stop-lever for shifting the same into retracted inoperative position, a reciprocating rod connected with the lateral arms of said angular levers, a treadle-rod, a toggle connection intermediate the treadle-rod and said reciprocating rod, a pattern-cam provided with a tripping point acting upon said latch-lever to disengage it from the stop-lever, means connected with the stop-lever for bending the toggle device to permit the opening of the work-holder, and a trip-lever disposed adjacent said latch-lever and in the path of movement of said tripping point and adapted to engage a member of said toggle connection to laterally displace the same as the latch-lever is shifted to release the stop-lever in stopping the machine.

21. In a sewing machine, the combination with stitch-forming mechanism, of a traveling work-holder having work-clamping jaws one of which is movable toward and from the other, a rock-lever mounted upon a fixed fulcrum and having a universal connection with the movable jaw of said work-holder, means for controlling the position of said rock-lever and comprising a toggle device including a pair of pivotally connected toggle links one of which is fulcrumed upon a fixed support and the other of which is fulcrumed upon said rock-lever, and means for straightening and bending said toggle device to close and open the work-holder.

In testimony whereof, I have signed my name to this specification, in the presence of two subscribing witnesses.

CHARLES M. HORTON.
